UNITED STATES PATENT OFFICE.

JACOB WALTHER, OF WINNIPEG, MANITOBA, CANADA, ASSIGNOR OF THREE-FOURTHS TO ANDREW WALTHER, THOMAS JAMES HARPER, AND JAMES WILLOUGHBY, OF WINNIPEG, CANADA.

AUTOMATIC RAILWAY-GATE.

SPECIFICATION forming part of Letters Patent No. 762,457, dated June 14, 1904.

Application filed March 14, 1903. Serial No. 147,871. (No model.)

To all whom it may concern:

Be it known that I, JACOB WALTHER, a subject of the King of Great Britain, residing in the city of Winnipeg, county of Selkirk, Province of Manitoba, Canada, have invented certain new and useful Improvements in Automatic Railway-Gates; and I do hereby declare that the following is a full, clear, and exact description of the invention, such as will enable others skilled in the art to which it appertains to make and use the same.

At railway-crossings it frequently happens that accidents occur on account of the negligence or inefficiency of the watchman or gate-man.

This invention relates to the gates such as are usually employed at railway-crossings; and a principal object has been to provide a gate which shall be automatically operated by the trains.

A further object has been to construct the gate so that it will operate not only as a safeguard to prevent persons crossing the track when a train is approaching, but is adapted so that it will constitute in a certain position a cattle-guard adapted to prevent cattle when driven across the track from straying along the track.

The gate normally occupies a position transversely of the rails, and throughout this specification this position will be referred to as the "open" position for the gate, considering the gate from the point of view of a person crossing the tracks.

The invention consists in a certain arrangement and combination of parts to be more fully described hereinafter and definitely set forth in the claims.

In the drawings which fully illustrate my invention, Figure 1 is a plan view showing the same largely diagrammatically, this figure being broken away, as will be readily understood. Fig. 2 represents, also in plan and upon an enlarged scale, the principal portion of the gate-operating mechanism and is partly in section for the purpose of greater clearness. Fig. 3 is a side elevation, a part of

which is shown in section, taken substantially upon the line 3 3 of Fig. 6. Fig. 4 is a cross-section taken upon the line 4 4 of Fig. 5. Fig. 5 is a fragmentary sectional plan of part of the mechanism shown in Fig. 3, the section being taken substantially along the line 5 5 of that figure. Fig. 6 shows a portion of the mechanism in plan, a portion being in section, as indicated, so as to show substantially the same mechanism which is shown in Fig. 5, displaying its method of connection with the other mechanism. Fig. 7 is a cross-section of Fig. 6, taken substantially on the line 7 7, while Fig. 8 represents a longitudinal section taken upon this same figure along the line 8 8. Fig. 9 is a section in a plane at right angles to the track and passing through the gate-posts shown at the right of Fig. 2 and 65 showing the arrangement of the mechanism for swinging the gate. Fig. 10 is a vertical section through Fig. 4, substantially on the line 10 10.

The same numerals of reference denote like parts in all the figures of the drawings.

Before proceeding to a detailed description of the parts it may be said that in its preferred form the gate comprises four horizontal doors or bars pivotally mounted upon posts arranged at the corners of a square. As will appear hereinafter, these guards are adapted to swing all in unison. As shown in Fig. 1, the two guards on the same side of the track coöperate to form a barrier before the railway-crossing. These guards, however, may swing in the manner described, so that they are disposed across the track, in which latter position each guard coöperates with the guard lying opposite it on the other side of the track, as will be readily understood. It should be understood that the gate is swung open or closed by the force of a spring, the mechanism being arranged for extending these springs and maintaining them extended until released, which release is operated by the passing of a train. The mechanism employed naturally divides itself into three groups of mechanism. The first group may be called the "contact"

mechanism, its function being to be operated by the passing of a train to set certain other mechanism in operation. The second group may be called the "actuating" mechanism. 5 This group includes the springs referred to for operating the gate and parts incident to their use or connected with them. The third group forms more properly a part of the gate, and for this reason the last group of mechanism will be referred to as the "gate" mechanism.

Referring to the parts by numerals, 1^c 1^d 1^a 1^b indicate the four gate-posts, each of which is rotatably mounted upon a suitable step bearing or block 2 and which may be suitably braced at the top by ties or braces 3. Upon each of these posts is mounted a built-up bar or frame 4, which is adapted to be swung horizontally when the post is rotated, 20 and they constitute the guards, as aforesaid. Near the foot one pair of these posts, which lie at opposite points on either side of the track, are provided with spiders 5, which comprise simply four radial arms disposed at right angles to each other, as indicated. The other pair of posts is provided with oppositely-extending radial arms 6, there being, however, only two of these upon each post. These arms 5 and 6 are connected by tie-rods 7, 25 which cross between the posts, as indicated, connecting with links 8 at their extremities. From this construction it will appear that if any post were rotated it would communicate its motion to its companion post upon 30 the same side of the track, but in an opposite direction. That pair of arms 5 which is not in connection with the links 8 is connected with other mechanism adapted to rotate the post, wherefore the guard which it carries 35 may be thrown to its other position, transmitting its movement to its companion through the mechanism described. For this purpose double bell-crank levers 9 and 10 are employed adapted to move in a horizontal plane. The 40 bell-crank lever 9 comprises the oppositely-extending arms 11 and 12, the former of which connects, by means of the links 13, 14, and 15, with an arm 5, carried by the post 1^a. The arm 12 connects, by means of the links 16, 17, 45 and 18, with an arm 5 of the post 1^b. The third arm 19 of the bell-crank lever 9 connects, by means of a link 20, with a draw-bar 21, which draw-bar is adapted to be actuated by the actuating mechanism, as aforesaid, so that 50 it controls the position of the bell-crank lever 9. It should be observed that the links 15 and 18 and the links connected, respectively, with them are so arranged that a movement of the draw-bar 21 will be transmitted to the posts 55 1^a and 1^b, so that they would rotate in opposite directions. It may be stated, however, that this bell-crank lever 9 operates only to move the gate to one position, a lever 10 being adopted for moving the gate to its opposite position. In each case the force which is

applied is that of tension. The bell-crank lever 10 is controlled by a draw-bar 22, and links 23, 24, and 25 connect the bell-crank 10 with the post 1^a, as indicated. A tie-bar 26 and links 27 and 28 afford means for connecting 70 this same bell-crank lever 10 with the post 1^b. From this arrangement it will appear that if a pull be made upon the draw-bar 22 the movement of the bell-crank lever 10 would be transmitted to the posts 1^a 1^b and operate to rotate 75 them in opposite directions. Viewing the mechanism as shown in Fig. 2, it will appear that if a pull were exerted upon the draw-bar 21 the gate would be swung from the position in which it is shown, so that it could assume 80 a position which we call the "open" position, wherein the guards 4 are disposed transversely of the track, and it should appear that when they are in this latter position a pull upon the draw-bar 22 would operate to return them to 85 the position in which they are shown. This mechanism for connecting the gates or guards so that they may be actuated by the draw-bars 21 and 22 is inclosed, as indicated, in a suitable box or casing 29, surmounted by a proper 90 platform or floor 30, over which vehicles or persons pass in crossing the rails 31.

Referring now to the mechanism for actuating the gate, which mechanism is most clearly shown in connection with Figs. 3, 4, 5, 6, and 10, this mechanism is carried within a suitable box or casing 32. There are provided springs 33 and 34, preferably helical springs, as indicated, and disposed substantially horizontally. At one extremity they attach, respectively, to catch-bars 35 36, and these catch-bars pass, respectively, through openings 37 and 38, formed in certain locking-plates 39 and 40, as indicated. It will appear that these locking-plates 39 and 40 are guided vertically and drawn upwardly by springs 41, and upon their lower edges each of the catch-bars 35 36 is provided with a notch or catch 42. From this construction it will appear that if either of the catch-bars 35 36 were 110 pulled so as to extend its spring sufficiently its notch or catch 42 could be engaged by its corresponding locking-plate, so that either of the springs 33 or 34 could be maintained extended. In the figures the spring 33 is shown 115 so extended. It should be understood that that these springs 33 34 supply the force for operating the gate, one of them always being extended, while the other is relaxed. For this purpose each of the catch-bars has secured to it a small bracket 43, which brackets connect, by means of small chains 44, respectively, with the draw-bars 21 22, to which reference has already been made. From the arrangement described it follows that if the 120 spring 33 were suddenly released it would operate to open the gate, and if the spring 34 were in tension and suddenly released it would operate to close the gate, and it will appear as the description progresses that the passing 125 130

of a train automatically releases whichever of these springs is in tension, so that the gate may be returned thereby. Proceeding further to describe the mechanism immediately connected with the springs 33 and 34, it will appear that links 45 attach, respectively, to the extremities of the catch-bars 35 36, which catch-bars are offset, as indicated at 46. These links 45 are attached to levers 47, which swing in a vertical plane about the pivot-point 48, and their opposite extremities connect with links 49 for the purpose which will appear hereinafter. It should appear that the links 45 connect with the levers 47 substantially at their middle points, the outer extremities of the links 45 being connected with pull-rods 50 51, respectively, and these pull-rods 50 and 51 are adapted to be actuated by the contact mechanism, which will be described later. Before indicating that, however, the mechanism will be described which effects the releasing of either of the springs 33 34. To accomplish this, there are provided substantially beneath the locking-plates 39 and 40 two bell-crank levers 52 53, the upper arms of which are connected, as indicated, with the upper arms of the levers 47 by means of links 54 and chains 55, and it will be observed from an inspection of Fig. 5 that these links 54 extend so as to cross each other, so that one of the levers 47 which connects with the catch-bar 36 may actuate the locking-plate 39, being adapted to actuate this locking-plate because the lower extremity thereof is connected with the lower arm of the bell-crank lever 52 by means of a chain 56. A similar chain 57 connects the locking-plate 40 with the bell-crank lever 53, so that if either of the pull-bars 50 or 51 is actuated it will operate not only to extend and lock its corresponding spring in an extended position, but will also operate to release the other spring in the manner described to bring about an actuation of the gate mechanism, as will be readily understood. The links 49, to which reference has already been briefly made, connect, respectively, with pull-bars 58 59. These latter pull-bars are for the same purpose as are the pull-bars 50 and 51; but it will be observed they extend in an opposite direction, wherefore they are intended to be actuated by the contact mechanism lying in an opposite direction from the gate, as will be readily understood.

Proceeding now to a description of the contact mechanism, which operates automatically to actuate the mechanism just described, the contact mechanism is most clearly illustrated in Figs. 6, 7, and 8. It should be said that this contact mechanism is actuated by the flange of a wheel upon the first car in the train, which is of course usually the locomotive, and this contact mechanism, as was stated, comprises two sets substantially similar, which sets are located at some distance from the gate, and this distance will be determined by

the period during which the gate is intended to be closed before the train passes and also by the lengths of the trains which usually pass. Just inside the rail and near its head are provided two contact-plates 60 and 61, which overlap each other, as indicated at 62. These plates are adapted to be engaged by the periphery of the flange of the car-wheel and depressed, and, as stated above, an arrangement of mechanism is adopted in connection with them which enables one of them when depressed by a wheel to depress automatically the other plate. Thus in Fig. 8 a train passing in the direction of the arrow would depress the plate 60, and this plate as it descended would cause the plate 61 to descend. As the plate 60 descended it would actuate its corresponding pull-bar 59; but the depressing of the plate 61, caused by the plate 60, would not actuate the pull-bar 58, which pull-bar is connected with the plate 61, however, in the same manner in which the pull-bar 59 is connected with the plate 60. It will be observed that the plate which is inclined most advantageously for contact with the flange is the plate first moved by the wheel, and the automatic depressing of the succeeding plate is desirable and perhaps necessary in order to prevent damage to the mechanism from the nature of the contact which would be made by the flange of the wheel with the extremity of the succeeding plate near the point 62. The construction of these plates and the mechanism actuated by them will be now described. Near their extremities the plates are provided with longitudinal guiding-openings 63, through which pass studs 64, mounted in suitable cross members 65, and the extremities of the plates may be curved slightly upwardly, as indicated. Near their inner extremities the plates are provided, respectively, with lugs 66, to which are attached, respectively, links 67 68, the latter of which is provided with an offset extension 69, wherefore it constitutes a lever which is pivoted at 70 to a slide 71, which is vertically guided in a frame 72, the construction being identical for both of the plates 60 and 61. Each of the slides 71 is provided with a lug 73, to which are attached links 74, connected with a bell-crank lever 75, which bell-crank lever is pivoted to the frame at 76, as indicated, so that it is adapted to move in a substantially vertical plane, its other arm being connected with links 77 and 78, as shown, the link 78 being at its outer extremity connected with a link 79, which last link is connected with a bell-crank lever 80, pivoted to the frame at 81, so that it moves in a horizontal plane with the link 79, and these two bell-crank levers 80 are connected, by means of short chains 82, respectively, with the pull-rods 58 and 59. The other contact-plates, represented, respectively, by 83 and 84, are connected by a similar mechanism respectively with the pull-rods 50 and 51. Between

the two slides 71 a bell-crank lever 85 is mounted upon the frame 72, and links 86 connect it, respectively, with the lower extremities of the extensions 69, and other links 87 5 are attached at the same point and are connected with springs 88, the extremities of which springs are attached to lugs 89, carried by the under sides of the contact-plates 60 and 61. From this construction it should 10 appear that the springs 88 are adapted to maintain the contact-plates normally in an elevated position, in which they are shown in Fig. 8. Now suppose the flange of a wheel 15 has come in contact with the upper side of the plate 60. This contact depresses the plate, the outer extremity of which is projected outwardly, so that the upper ends of the slots 63 approach the studs 64. At the same time the slide 71 corresponding to this contact- 20 plate is depressed, and as it descends it actuates the bell-crank lever 75, affecting the springs 33 and 34 in the manner which has been described; but as it descends the link 86 descends with it, which rocks the bell-crank 25 lever 85 in the direction of the arrow shown in Fig. 8, and this rocking of the link 85 moves the more distant lever 68, so that the contact-plate 61 is moved outwardly and downwardly, so that it too becomes depressed 30 likewise with the contact-plate 60; but this movement of the contact-plates does not affect the other slide 71. Hence it cannot affect or operate its corresponding pull-rod 58. Now, of course, when the direction in which 35 the wheel approaches is opposite to that supposed the mode of operation of this entire mechanism is reversed, the contact-plate 61 being first depressed, so that it actuates its pull-rod 58 and depresses automatically the contact-plate 60 without affecting the pull- 40 rod 59.

The mode of operation of the entire mechanism may be briefly outlined as follows: Suppose now that the gate is in its normal or 45 open position, which will be understood to mean that it extends across the track. Suppose now that the train approaches in the direction of the arrows shown in Fig. 8. The contact-plate 60 will be depressed by the flange 50 of the wheel in the manner described, depressing the slide 71 and actuating the pull-rod 59, so that it releases the spring 34 in a manner which has already been described. As this takes place the spring 33 is locked in 55 the extended position in which it is shown in Fig. 6. The contraction of the spring 34 actuates the rod 22, which throws the gate into the position in which it is shown in Fig. 2 to allow the train to pass. Moreover, as the 60 contact-plate 60 is depressed it operates to depress the contact-plate 61 without affecting its corresponding pull-rod 58, wherefore the spring 33 does not become released, and the gate therefore remains in a fixed position. 65 Now as the remaining wheels of the train pass

successively over these plates they simply depress them successively without in any way affecting the arrangement of the mechanism in connection with the springs 33 and 34. When the train has passed the gate a sufficient 70 distance, the contact-plate 83 is then depressed, operating its corresponding pull-rod 51, so that the spring 33 is now released and by its contraction through the draw-bar 21 operates to return the gate to its former position; 75 but actuating the pull-rod 51 extends once more the spring 34, which is locked automatically, as before, in the extended position, wherefore the mechanism is set again so that the spring 34 when released will throw the 80 gate again for the train to pass. Depressing the contact-plate 83 automatically depresses the contact-plate 84 without, however, affecting in any manner its corresponding pull-rod 50, for the reason set forth. 85

The spring-releasing mechanism, which was only briefly touched upon in the paragraph preceding, operates in this manner: When the pull-rod 59 is actuated, it extends the spring 33 by means of one of the levers 47, and a 90 link 54 leads across from this lever, connecting with a bell-crank 53, which bell-crank by means of the chain 57 draws down the locking-plate 40, so as to release the catch-ball 42, removing the catch-ball from the notch 95 42 in the manner described.

In order to allow pedestrians to pass through the gate when disposed to cross the path, the extremities of the guards 4 are formed into a frame 90, which is mounted upon a vertical 100 pivot 91, a member 92 being carried thereby, projecting toward the post and attached to a spring 93, wherefore the frame 90 normally constitutes an extension of the guard. The arrangement, it will be observed, is such as 105 to enable these frames 90 to swing outwardly from the track when the gate is in the position in which it is shown in Fig. 2.

While I have shown in the accompanying drawings the preferred form of my invention, 110 it will be understood that I do not limit myself to the precise form shown, for many of the details may be changed in form or position without affecting the operativeness or utility of my invention, and I therefore reserve the right to make all such modifications as are included within the scope of the following claims or of mechanical equivalents to the structures set forth. 115

Having thus described my invention, what 120 I claim as new, and desire to secure by Letters Patent, is—

1. In a railway-gate, in combination, guards adapted to extend across the railway or the roadway, springs adapted to move said guards 125 in opposite directions, members adapted to be engaged by passing trains, mechanism actuated by said members for independently extending said springs, means for normally maintaining at least one of said springs in an 130

extended position, and automatic means for releasing said springs, substantially as described.

2. In a gate of the class described, in combination, guards adapted to extend across the railway or the roadway, springs adapted to move said guards in opposite direction, means actuated by an approaching train for extending either of said springs, means for locking a spring so extended against contraction, and means also actuated by the train for releasing either of said springs, substantially as described.

3. In a gate of the class described, in combination, guards adapted to extend across the railway or the roadway, springs adapted to move said guards into either of these positions, pull-rods, means whereby said pull-rods may extend said springs, means for locking said springs in an extended position, means whereby said pull-rods may release said springs, and members actuated by a passing train and adapted to control the operation of said pull-rods, substantially as described.

4. In a gate of the class described, in combination, guards adapted to extend across the railway or the roadway, springs adapted to move said guards in opposite directions, catch-bars connected with said springs, locking-plates, means whereby said locking-plates and said catch-bars may engage to maintain said springs in an extended position, members adapted to be actuated by a passing train, and means operated by said members for extending said springs and moving said locking-plates, substantially as described.

5. In a gate of the class described, in combination, guards adapted to extend across the railway or the roadway, springs adapted to move said guards between the two positions thereof, catch-bars connected with said springs, locking-plates, means whereby said locking-plates may engage said catch-bars, means for restraining said locking-plates, means adapted to be actuated by a passing train, and means actuated thereby for extending said springs and moving said locking-plates, substantially as described.

6. In a gate of the class described, in combination, guards, contact-plates inclined in opposite directions and adapted to be depressed by the flange of a car-wheel, mechanism connecting one of said members with said guards, other mechanism connecting the other of said members with said guards, means whereby the depression of one of said members may actuate said guards, and means whereby depressing said last member may depress the remaining member, substantially as described.

7. In a gate of the class described, in combination, guards, a pair of contact members adapted to be depressed by a passing car, slides adapted to be depressed respectively by the depression of said contact members, mechanism connecting said slides with said guards,

and means whereby the depression of one of said contact members may depress the other of said contact members without affecting the slide corresponding thereto, substantially as described.

8. In a gate of the class described, in combination, guards, contact members adapted to be depressed by a passing train, slides connected with said contact members, mechanism connecting said slides with said guards, a member connecting said slides, said member being adapted to be actuated when one of said contact members is depressed, and means actuated by said member for preventing the depression of the second slide, by the second contact member, substantially as described.

9. In a gate of the class described, in combination, guards, contact members adapted to be depressed by a passing train, slides connected therewith and adapted to be depressed by said contact members, mechanism connecting said slides with said guards, a bell-crank lever between said slides, mechanism connecting said bell-crank lever with said contact members, wherefore the depression of the second slide by the second contact member is prevented, substantially as described.

10. In a gate of the class described, in combination, guards, contact members adapted to be depressed by a passing train, slides, levers connecting said contact members with said slides, and mechanism connecting said levers, whereby the depressing of the second slide by the second contact member is prevented, substantially as described.

11. In a gate of the class described, in combination, guards, contact members adapted to be depressed by a passing train, means for guiding the same longitudinally, slides therebelow, levers connecting said contact members with said slides, a third lever connecting said levers, and mechanism connecting said slides with said guards, substantially as described.

12. In a gate of the class described, in combination, guards, contact-plates, means for guiding the same longitudinally, levers connected therewith, slides carrying said levers, wherefore the depressing of one of said contact members may depress its corresponding slide, a third lever connecting said levers, and springs normally retaining said contact members in an elevated position, substantially as described.

13. In a gate of the class described, in combination, guards, contact members adapted to be depressed by a passing train, means for guiding said contact members longitudinally, slides, levers carried thereby and attached to said contact members, mechanism connecting the lower extremities of said levers, and springs constraining said levers to maintain said contact members in an elevated position, substantially as described.

14. In a gate of the class described, in combination, oppositely-inclined contact-plates

adapted to be depressed by a passing train, means for guiding said contact-plates longitudinally and parallel with the track - rail, slides vertically movable therebeneath, substantially vertically disposed levers carried by said slides and connected with said contact-plates, a bell-crank lever between said slides, links connecting the same with the lower extremities of said levers, springs restraining said levers and attached to said contact-plates, guards at the railway-crossing, and mechanism connecting said slides with said guards, substantially as described.

15. In a gate of the class described, a guard, a movable extension pivotally attached to said guard near the outer extremity thereof, and

a helical spring disposed substantially longitudinally in the same plane with said guard and connecting said guard with said extension.

16. In a gate of the class described, in combination, a guard, an extension pivotally attached thereto and having a rearwardly-extending arm, and a helical spring attaching to said arm and connecting the same with said guard to maintain said extension in substantially the same plane with said guard. 25

In witness whereof I have hereunto set my hand in the presence of two witnesses.

JACOB WALTHER.
